UNITED STATES PATENT OFFICE.

JOHN R. SIEGER, OF MINNEAPOLIS, MINNESOTA.

WRENCH.

Application filed December 18, 1924. Serial No. 756,630.

To all whom it may concern:

Be it known that I, JOHN R. SIEGER, a citizen of the United States, residing at Minneapolis, in the county of Hennepin and State of Minnesota, have invented certain new and useful Improvements in Wrenches, of which the following is a specification.

My invention relates to wrenches, and 10 has for its object to provide a wrench which may be quickly and effectively adjusted to fit various sizes of objects operated upon.

Another object of the invention resides in 15 providing a fixed jaw and a movable jaw having ratchet teeth thereon, and a dog pivoted to said fixed jaw adapted to engage said ratchet teeth to hold said movable jaw from movement relative to said fixed jaw.

A still further object of the invention re- 20 sides in providing a release for said dog capable of being operated by the exertion of pressure thereon, whereby said dog may be released to permit of adjusting the wrench.

A feature of the invention resides in con- 25 struction said movable jaw with a shank on which the ratchet teeth are formed, and of constructing said release in such a manner that the same passes around said shank so that the engaging portion of said release 30 lies along the exterior surface of said shank.

Other objects of the invention reside in the detailed construction of the same as disclosed in the following specification, drawing, and claims.

35 In the drawings illustrating my invention in one form:

Fig. 1 is an isometric view of one form of my invention in actual use;

Fig. 2 is an enlarged fragmentary view 40 of the invention illustrated in Fig. 1;

Fig. 3 is a sectional view taken on line 3—3 of Fig. 2;

Fig. 4 is a plan view of a modified form 45 of a wrench with a portion removed to illustrate the interior construction thereof; and

Fig. 5 is an isometric view of the jaw 50 guide shown in Fig. 4.

In the drawings I have illustrated my invention as particularly adapted to be used as a pipe wrench, tho it can be readily understood that the invention is most readily used in this manner the same can be also used in conjunction with other wrenches and other devices.

55 My invention comprises a fixed jaw 10 and a movable jaw 11. The jaw 10 is made

with a slot 12 which fits over a tongue 13 formed on the end of a handle 14. The jaw 11 is integrally attached to a shank 15 which is offset in relation thereto so that said shank may lie parallel to the handle 14 when in its assembled position. Around the shank 15 is positioned a U-shaped guide 16 which is formed with a back 17 and two arms 18. Between these arms are positioned two bars 19 and 20 which together with the arms 16 and the back 17 form a guideway thru which the shank 15 extends. The arms 18 straddle the handle 14 and are pivoted to it by means 65 of a bolt 21.

The device for holding the jaw 11 in adjusted position relative to jaw 10 can best be seen in Fig. 2. As will be noted the jaw 10 extends outwardly beyond the handle 14 as indicated at 22. To this portion of said jaw is pivoted a dog 23 which is adapted to engage ratchet teeth 24 formed along the inner edge of the shank 15. This dog is held in engagement therewith by means of 75 a leaf spring 26 riveted to the handle 14. A similar spring 27 also pivoted to the handle 14 at the same place as spring 26 and engaging the bar 20 holds the jaw 11 so that said jaws are always in engaging 80 position relative to the object upon which the wrench is to be used.

In the guide 16 a slot 35 is provided which extends only across the back 17. Along the sides 18 are formed two grooves or depressions 36 which serve as guideways for the release 29. The release 29 is constructed of wire as shown in the drawings and has the ends thereof bent inwardly to form two hooks 37 and 38 which are adapted to engage 90 within slots 39 extending along the dog 23 on each side thereof. In assembling the device the dog 23 is first pivoted to the jaw 10. The release 29 is next slid into the grooves 36 thru the slot 35, and the assemblage placed upon the handle 14, the hooks 38 being simultaneously slid into the grooves 39. Upon being properly positioned the bolt 21 is inserted after which the springs 26 and 27 are attached. By sliding the jaw shank 15 into 100 the guide 16, the device is ready to be used. This device is advantageous in that a neater construction is provided in which the greater portion of the release and dog are concealed, thereby preventing the wrench from being 105 readily clogged with dirt. At the same time a somewhat cheaper construction is provided. 110

The use of the device is obvious. The release 29 is first depressed, which permits the movable jaw 11 being moved along the guide 16. The same is then adjusted until the 5 jaws 10 and 11 engage the object upon which the device is to operate. Upon removing the pressure from the release, dog 23 engages one of the ratchet teeth 24 which holds jaw 11 from outward movement. Upon grasping 10 handle 14 the object positioned between jaws 10 and 11 may be rotated in the usual manner.

If desired the guide 16 may be made from a metal stamping as shown in Fig. 5. A 15 portion of the metal of the arms 18 indicated at 40 on both sides thereof is severed from the major portion of said arms along an edge thereof and bent inwardly towards each other as clearly indicated in Figs. 4 and 5 to 20 form oppositely facing lugs. These lugs take the place of the bars 19 and 20 in the other form of the invention.

My invention is advantageous in that it 25 provides a simple and inexpensive wrench construction whereby the same may be quickly and conveniently adjusted to fit any size of object which it is desired to turn or grip. The device has the release positioned so that it is convenient to manipulate thereby making 30 the adjustment very rapid and convenient. The device can be made at a cost not to appreciably exceed the cost of the ordinary wrench.

In compliance with the patent statutes, I 35 have described my invention in the form which I consider the best embodiment thereof, but I desire to have it understood that the invention may be put to other uses and 40 constructed in different forms within the scope of the following claims.

Claims:

1. A wrench comprising a fixed jaw, a 45 movable jaw, a shank attached thereto, ratchet teeth formed on said shank, a dog pivoted to said fixed jaw adapted to engage said ratchet teeth, a U-shaped guide enveloping said shank and secured to said fixed jaw, said guide being formed with a pair of inwardly extending grooves communicating 50 with an opening in said guide at the ends of said grooves remote from said jaw, a U-shaped release surrounding said shank being positioned within said grooves and lying be-

tween said shank and the walls of said guide with the end thereof protruding through 55 said opening, said dog being formed with outwardly-facing similarly situated slots and inwardly-extending hooks formed on said release adapted to engage within said slots.

2. A wrench comprising a fixed jaw, a handle secured thereto, a movable jaw, a shank attached to said movable jaw and lying adjacent said handle, ratchet teeth formed on said shank, a dog pivoted to said 60 fixed jaw adapted to engage said ratchet teeth, a U-shaped guide having a back extending along said shank and arms extending across the same and pivoted to said fixed jaw, said back being formed with a transverse slot, guideways formed on said arms extending across said shank and communicating with said slot, a release movable along said guideways and adapted to extend into said slot, said dog being formed with oppositely-facing longitudinal grooves, and inwardly bent hooks formed on the end of said release adapted to engage said dog within 65 said slots for disengaging the same from said ratchet teeth.

3. A wrench comprising a fixed jaw, a handle secured thereto, a movable jaw, a shank formed thereon lying adjacent said handle, ratchet teeth formed on said shank, a dog pivoted to said fixed jaw adapted to 70 engage said ratchet teeth, a U-shaped guide formed of sheet-metal pivoted to said handle, inwardly turned lugs formed on the ends of the guide to hold said guide slidably mounted relative to said shank, outwardly 75 pressed grooves formed along the sides of the guide extending radially from the point of pivot thereof, said guide being formed with an opening connecting said grooves at the ends thereof, said dog being formed 80 with outwardly-facing longitudinally extending open-ended slots, a U-shaped wire release positioned within said slots between said guide and said shank, having a thumb-engaging portion projecting thru said opening, and inwardly bent hooks formed on said release engaging within the slots in said dog and adapted to be inserted thru the 85 open ends thereof.

In testimony whereof I affix my signature.

JOHN R. SIEGER.
